UNITED STATES PATENT OFFICE.

GUSTAVE M. FAUSER, OF NEW YORK, N. Y., ASSIGNOR TO SUSQUEHANNA SILK MILLS,
OF NEW YORK, N. Y.

DESIGN FOR TEXTILE FABRIC.

• 41,935.

Specification for Design. Patented Nov. 21, 1911.

Application filed June 22, 1911. Serial No. 634,871. Term of patent 3½ years.

To all whom it may concern:

Be it known that I, GUSTAVE M. FAUSER, a citizen of the United States, residing at New York, in the county of New York and State of New York, have invented a new, original, and ornamental Design for a Textile Fabric, of which the following is a specification, reference being had therein to the accompanying drawing.

The figure is a plan view of a portion of a textile fabric showing my design.

I claim:

The ornamental design for a textile fabric as shown.

In testimony whereof I hereunto affix my signature in presence of two witnesses.

GUSTAVE M. FAUSER.

Witnesses:

WILLIAM H. SCOTT, Jr.,

ALBERT C. SCHUTZINGER.
